UNITED STATES PATENT OFFICE

158,956

SLIPPER

Marlin F. Haas, Los Angeles, Calif.

Application January 4, 1950, Serial No. 6,998

Term of patent 7 years

(Cl. D7—7)

To all whom it may concern:

Be it known that I, Marlin F. Haas, a citizen of the United States, residing in Los Angeles, in the county of Los Angeles, State of California, have invented a new, original, and ornamental Design for a Slipper, of which the following is a specification, reference being had to the accompanying drawings, forming a part thereof.

I claim:

The ornamental design for a slipper, substantially as shown and described.

MARLIN F. HAAS.
